DESIGN FOR A ROTARY TOOTHBRUSH EXTENSION

William T. Brennan, Dunmore, and William P. Kennedy, Scranton, Pa., assignors to Scranton Electric Toothbrush Corporation, Scranton, Pa.

Application February 27, 1940, Serial No. 90,542

Term of patent 14 years

To all whom it may concern:

Be it known that we, William T. Brennan and William P. Kennedy, citizens of the United States, residing, respectively, at Dunmore, in the county of Lackawanna and State of Pennsylvania, and at Scranton, in the county of Lackawanna and State of Pennsylvania, have invented a new, original, and ornamental Design for a Rotary Toothbrush Extension, of which the following is a specification, reference being had to the accompanying drawing, forming part thereof.

Figure 1 is a plan view of a rotary toothbrush extension showing our new design.

Figure 2 is a side elevation of the toothbrush extension shown in Figure 1,

Figure 3 is a sectional view through the stem at 3—3 of Figure 1,

Figure 4 is a sectional view through the stem at 4—4 of Figure 1,

Figure 5 is a sectional view through the brush and brush guard at 5—5 of Figure 1, and

Figure 6 is an end view of Figure 1 looking from right to left in the direction of arrow 6.

We claim:

The ornamental design for a rotary toothbrush extension, as shown.

WILLIAM T. BRENNAN.

WILLIAM P. KENNEDY.
